UNITED STATES PATENT OFFICE

162,877

ANGLE HEAD FOR ROTARY TOOLS

Julious A. Price, Castro Valley, and John D. Rutzebeck, Hayward, Calif.

Application September 15, 1950, Serial No. 12,194

Term of patent 14 years

(Cl. D54—13)

To all whom it may concern:

Be it known that we, Julious A. Price and John D. Rutzebeck, citizens of the United States, residing respectively at Castro Valley, State of California, and Hayward, State of California, have invented a new, original, and ornamental Design for an Angle Head for Rotary Tools, of which the following is a specification, reference being had to the accompanying drawings, forming a part hereof, wherein,

Figure 1 is a perspective view showing our new design for an angle head for rotary tools.

Figure 2 is a front elevational view of the head.

Figure 3 is a side elevational view of the head.

We claim:

The ornamental design for an angle head for rotary tools, substantially as shown.

JULIOUS A. PRICE.
JOHN D. RUTZEBECK.
